In Canada August 10, 1950

Term of patent 14 years

(Cl. D34—15)

To all whom it may concern:

Be it known that I, Josephus Thompson, a citizen of the United States, residing at Covington, county of Miami, and State of Ohio, have invented a new, original, and ornamental Design for a Toy Horn, of which the following is a specification, reference being had to the accompanying drawing, forming part thereof.

Fig. 1 is a side elevational view of a toy horn, showing my new design;

Fig. 2 is a top plan thereof;

Fig. 3 is a bottom plan thereof;

Fig. 4 is a sectional view taken on line 4—4 of Fig. 1; and

Fig. 5 is a sectional view taken on line 5—5 of Fig. 1.

I claim:

The ornamental design for a toy horn, as shown.

JOSEPHUS THOMPSON.
